UNITED STATES PATENT OFFICE.

HOWARD I. GENTINE, OF SHELBYVILLE, ILLINOIS, ASSIGNOR TO AMERICAN
ATOMIZED FUEL COMPANY, OF SHELBYVILLE, ILLINOIS, A CORPORATION
OF SOUTH DAKOTA.

PULVERIZED-FUEL FEEDER AND MIXER.

1,419,730.

Specification of Letters Patent. Patented June 13, 1922.

Application filed December 10, 1920. Serial No. 429,832.

To all whom it may concern:

Be it known that I, HOWARD I. GENTINE, a citizen of the United States, and a resident of Shelbyville, in the county of Shelby 5 and State of Illinois, have invented a new and useful Pulverized-Fuel Feeder and Mixer, of which the following is a specification.

My invention relates to pulverized fuel feeders and mixers and its primary object is to provide a mechanism wherein the pulverized fuel will be continuously fed to a mixing chamber where it is mixed with air and thence discharged into the fire box of 15 a furnace.

A further object of the invention is to provide a fuel feeder wherein fuel is kept in motion by a rotating turn table and thus caused, by centrifugal action, to be fed to 20 the furnace fire box.

It is also an object of the invention to provide means wherein the fuel supply and air supply may be regulated through the medium of a common operating mechanism.

With the preceding and other objects and advantages in mind, the invention consists in the novel combination of elements, construction and arrangement of parts and operations to be hereinafter fully described, 30 claimed and illustrated in the accompanying drawings, wherein:

Figure 1 is a side elevation of the complete mechanism, parts being broken away;

Figure 2 is a top plan view of the same; 35 Figure 3 is a vertical sectional view looking toward the forward end of the mechanism; and

Figure 4 is a fragmentary elevation illustrating the manner in which the fuel hopper is supported.

Referring in detail to the drawings wherein like characters of reference designate like parts throughout the several views, the numeral 5 designates a base plate upon 45 which a fan casing 6, provided with an inlet pipe 7 and an outlet pipe 8, is mounted. Any suitable type of fan (not shown) is mounted in the fan casing 6 and includes a drive shaft 9. Also mounted on the base 5 50 is a support or bracket 10 upon which an electric motor 11 is mounted.

The numeral 12 designates a gear box, the gears of which have operative connection with the shaft 9 and the shaft 13 of the

motor 11. Rotatably supported on the gear box 12 is a vertical shaft 14 to the upper end of which a turn table or disk 15 is fixed. Secured to the shaft 14 below the disk 15 is a relatively large gear 16. A vertically disposed power shaft 17 has operative connection with the gears in the gear box 12 and carries, at its upper end, a drive pinion 18 meshing with the gear 16 to impart rotation thereto. Suspended in the floor or ceiling 19 is a hopper 20 in which the pulverized fuel is placed, and secured to the mouth of the hopper and overlying the turn table 15 is a rectangular bottomless casing 21.

Mounted in guides 22 at the forward end 70 of the casing is a vertically movable gate or slide valve 23 adapted to be adjusted to regulate the quantity of pulverized fuel to be fed from the rotating disk or turn table.

Communicating with the air inlet pipe 7 is a vertically arranged discharge chute 24 which is disposed forwardly of the hopper 21 and is formed with a longitudinal slot 25 in which the disk or turn table 15 projects. A regulating slide valve 26 is 80 mounted in the upper end of this chute and controls the fuel from the disk to the chute. In order to prevent the fuel from moving off the turn table after the same is fed out beyond the casing 21, there is provided a forwardly extending wall 27 which is mounted upon the forward wall of the casing 21.

A butter-fly valve 28 is pivoted in the pipe 7 to control the air passing to the casing 6, and pivotally connected with an arm 29 fixed to the axis of the valve 28 is a link 30 pivoted intermediate its ends, as shown at 31. An operating lever 32 has one end pivoted to the casing 21 and to this operating lever 32 the upper end of the link 30 is pivotally connected. A link 33 has one end pivotally connected with the slide or gate valve 23 and its opposite end pivotally connected with the operating lever 32. 95 100

It will thus be seen, that upon manipulating the lever 32, both the butter-fly valve and the gate valve may be adjusted to permit the fuel and air to be fed to the casing 6 in the proper proportions. In order to 105 prevent the fuel from massing in the hopper 20, a pair of vertically arranged agitator blades 34 is fixed to the upper end

of the shaft 14, which blades project into the hopper 20.

In the operation it will be obvious that as the fuel gravitates from the hopper 20 it is fed outwardly upon the disk 15 by centrifugal force and as the fuel banks or piles at the wall 27, it is gradually thrown through the slot 25 and carried to the pipe 7 by way of the discharge chute 24. The amount of fuel to be permitted to pass from the disk 15 to the chute 24 is governed by the valve 26.

It is to be understood that the form of my invention herein shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States, is:-

25 1. A mechanism of the character described comprising a fan casing having an inlet and an outlet, a hopper supported at one side of the fan casing adapted to contain fuel to be fed to the latter, a vertically movable valve for controlling the amount of fuel to be fed from the casing, a rotatable turn table mounted below the hopper, a discharge chute arranged forwardly of the turn table and communicating with the fan inlet, and 30 a forwardly extending wall projecting from the hopper and overlying the turn table and adapted to prevent the fuel from moving with the latter.

2. A mechanism of the character described comprising a fan casing having an inlet and an outlet, a hopper supported at one side of the fan casing adapted to contain fuel to be fed to the latter, a vertically movable valve for controlling the amount of fuel to be fed from the casing, a rotatable turn table mounted below the hopper, a discharge chute arranged forwardly of the 35

turn table and communicating with the fan inlet, a forwardly extending wall projecting from the hopper and overlying the turn table and adapted to prevent the fuel from moving with the latter, and gearing operatively connecting the motor with the turn table.

3. A mechanism of the character described comprising a fan casing having an inlet and an outlet, a hopper supported at one side of the fan casing adapted to contain fuel to be fed to the latter, a vertically movable valve for controlling the amount of fuel to be fed from the casing, a vertically arranged rotatable shaft, a turn table fixed to the upper end thereof and disposed below the hopper, a discharge chute arranged forwardly of the turn table and communicating with the fan inlet, a forwardly extending wall projecting from the hopper and overlying the turn table and adapted to prevent the fuel from moving with the latter, a relatively large gear fixed 70 to the shaft, a drive pinion meshing with the gear, and a motor operatively connected with the drive pinion.

4. A mechanism of the character described comprising a fan casing having an inlet and an outlet, a hopper supported at one side of the fan casing and adapted to contain fuel to be fed to the latter, a vertically movable valve for controlling the passage of fuel to the casing, a rotatable table disposed below the hopper, a discharge chute arranged forwardly of the rotatable table and communicating with the fan inlet and adapted to receive the fuel from the rotatable table, an air controlling valve arranged in the fan inlet, an operating lever pivoted to the hopper, a link connection between the lever and the vertically movable valve, and a link pivoted intermediate its ends and having one end operatively connected with the operating lever and its opposite end 80 operatively connected with the air controlling valve.

HOWARD I. GENTINE.
